UNITED STATES PATENT OFFICE.

HERBERT S. VALENTINE, OF PHILADELPHIA, PENNSYLVANIA, ASSIGNOR TO LINK-BELT COMPANY, OF PHILADELPHIA, PENNSYLVANIA, A CORPORATION OF ILLINOIS.

ELECTRIC CONTROLLING SYSTEM.

1,243,571.

Specification of Letters Patent. Patented Oct. 16, 1917.

Application filed June 30, 1915. Serial No. 37,346.

To all whom it may concern:

Be it known that I, HERBERT S. VALENTINE, a citizen of the United States, residing in Philadelphia, Pennsylvania, have invented certain Improvements in Electric Controlling Systems, of which the following is a specification.

One object of my invention is to provide a system for controlling a motor particularly of the type used on cranes and hoists, in which the apparatus shall be so arranged that a break at any point, and more especially, in the resistance, shall necessarily result in the operation of the holding brake.

It is further desired to provide a motor controlling system including a solenoid or similar brake, a controller, and controlling resistance, all so connected that a breakage in the resistance will cut off current from the brake winding and thereby cause setting of the holding brake at any running position of the controller.

Another object of my invention is to provide a novel combination of a hoisting motor, resistance and controller with the associated connections particularly designed to result in relatively highly efficient operation of said motor when it is used for lowering as well as when it is employed to hoist a load.

These objects and other advantageous ends I secure as hereinafter set forth, reference being had to the accompanying drawings, in which,

Figure 1 is a diagrammatic view of the apparatus comprising my invention, and

Figs. 2 to 7 inclusive are diagrams illustrating the connections of the apparatus included in my invention under various conditions of its operation.

In the above drawings 1 represents the armature and 2 the field windings of an electric motor, of which the latter is directly connected to one terminal of a body of resistance 3 designed to limit the current flow when said motor is short circuited and positively driven as a generator. Directly connected to the second terminal of the resistance 3 is a controller blowout winding 4

which is likewise connected in series with the winding of an electric brake 5. This latter may be of any suitable form designed to operate when its winding is deenergized, to prevent rotation of the motor armature,

but designed to release the armature or apparatus to which it is connected as long as said brake winding is supplied with suitable current.

For governing the operation of the motor I provide a controller, shown in Fig. 1 with its contacts and fingers as diagrammatically developed. Said fingers are indicated at 6 to 17 and are so placed as to coöperate with either of two sets of contact strips or segments preferably mounted on a rotary barrel of the well known form.

Banks of resistance 18, 19 and 20 are connected between the fingers 12—13, 13—14, and 14—15, and the finger 6 is connected to one terminal of a source of current supply, while the finger 17 is connected to the second terminal of such source. The finger 7 is permanently connected to one terminal each of the armature and field winding, while the finger 8 is connected to the second armature terminal and also to the finger 11. The finger 9 through a suitable conductor connects between the second terminal of the field winding and the resistance 3, while the finger 10 is connected to the conductor extending between the resistance 3 and the blowout winding 4.

The finger 12 is connected through the winding of the brake 5 to the second terminal of the blowout winding 4, while the fingers 15 and 16 are directly connected together. Without specifically describing the detail arrangement of the controller contacts or segments which coöperate with the various fingers 6 to 17 inclusive, it is noted that those to the right of the line of the fingers are designed to be utilized when the motor is operated to raise a load, and of these contacts the ones coöperating with the fingers 10 and 11 are extended so as to be in engagement with said fingers when the controller is in its off position. Since these contacts are permanently connected together, when the controller is in this position the motor is short circuited and its circuit consists of the elements shown in Fig. 7. Similarly, the contacts or segments to the left of the line of fingers are designed for use when a load is being lowered.

As the controller is operated to successively bring the contacts or segments X into engagement with their coöperating fingers, the apparatus is first connected as shown in

Fig. 6 with the field winding 2 in series with the armature and with the controlling resistance 18, 19 and 20, as well as with the blowout winding 4 and the brake winding 5 likewise in series. Thereafter the rotation of the controller barrel successively cuts out of circuit the resistance banks 18, 19 and 20, thereby causing the motor to be speeded up until it is finally connected directly across the line with the resistance 3 and electric brake winding 5 still in series with it, so that obviously an open circuit occurring in the resistance, necessarily deenergizes the winding of the brake solenoid, which when the system is used with a hoisting motor, at once causes application of the brake and prevents dropping of the load which is being raised.

If now the controller be turned from its full-on position to its off position, the motor under certain conditions will be driven by the load which it has been raising, so that when the controller cylinder is in such off position, the motor is short circuited through the resistance 3 and acts as a generator. Under these conditions the current flow is kept within predetermined limits by said resistance and the machine acts as a dynamic brake to prevent a dangerously rapid descent of the load.

When it is desired to drive the motor so as to positively lower the load, the moving of the controller barrel to bring the contacts Y into engagement with the various fingers causes the apparatus to be successively connected as indicated in Figs. 2 to 5 inclusive. On the first point the field winding 2 which is connected in series with the limiting resistance 3, the winding of the brake 5 and the resistance bank 20, is with them in parallel with the armature 1, and with the latter in series with the resistance 20. On the second and third points the connections of the armature remain as before while the flow of current through the field winding is weakened by first connecting it in series with the resistance bank 18 and then adding to its circuit the resistance bank 19. On the last point, the armature of the motor is directly connected across the line, while the current through the field is cut down as far as possible by connecting in series with it the three banks of resistance 18, 19 and 20. On all of these points the winding of the electric brake 5 is always in series with whatever part of the resistance is in circuit or is so connected that the cutting

off of current from the motor circuit will result in setting of the holding brake.

If, as is frequently the case, it is desired to prevent overtravel of the hoisting apparatus actuated by my controlling system, I provide a switch 25 in the line connecting the armature 1 of the motor with the line running between the field winding 2 and the finger 7, and also employ a conductor 26 running from said finger to a point in said line between the switch 25 and the armature 1. With such an arrangement of parts, after the motor has been operated to raise a load to a predetermined height, some part of the hoisting mechanism so engages the switch 25 as to open the same and thereby cut off current from the armature 1, whereupon the motor with its attached apparatus comes to rest.

Hitherto it has either been necessary for the overtravel switch 25 to be manually closed before the apparatus could again be put in service, or a separate trolley wire, with the extra contacts, fingers and connections were employed, but with the connections above described this is unnecessary, since if the controller be operated to bring the contacts Y into engagement with the various fingers, it will be noted that even though the switch 25 is open, current is free to flow from the finger 6 to the uppermost of the Y contacts, thence to the contact next beneath the same, the finger 7, conductor 26, through the armature 1, and through the finger 11 to the other apparatus of the system as previously described. The motor is thus started in such a direction as to lower the load and the switch 25 is closed by gravity or by the action of a spring.

This last described feature is an important element of my invention, for it permits of the reversal of the motor even while the overtravel switch is still open, and causes the automatic closing of said switch, so that after lowering the apparatus may be at once put into service to hoist a load.

I claim:—

A system including a motor; an overtravel switch therefor; and a controller for the motor including means for shunting said switch to permit reversal of the motor when said switch is open; said means including two conductors leading from one of the fingers of the controller and connected on opposite sides of said switch.

HERBERT S. VALENTINE.
